SNOW AND ICE MELTING DEVICE

Ramón Bonilla, New York, N. Y.

Application December 6, 1951, Serial No. 260,168

4 Claims. (Cl. 237—1)

1

This invention relates to new and useful improvements in devices for preventing the accumulation of snow on street surfaces.

More specifically, the present invention proposes the construction of a device supported at an elevated position above a street so as to melt falling snow to thereafter drop as rain and flow from the street and sidewalk surfaces into the usual catch basin of the sewer system in a manner to eliminate the expense of snow removal, to eliminate personal injury resulting from pedestrians slipping on accumulated snow and to eliminate vehicle skidding resulting in automobile damage and possible personal injury to vehicle passengers and pedestrians.

A further object of the present invention proposes characterizing the snow melting device by a main feeder pipe supported above the street so as not to interfere with vehicle and pedestrian traffic and from which branch pipes extend in opposite directions so that steam under pressure fed into the main feeder pipe will discharge from apertures formed in the branch pipes to melt the snow before it can fall onto the street and sidewalk surfaces.

Still further, the present invention proposes providing a hollow beneath the sidewalk at one end of the main feeder pipe and within which a steam generator heated by an oil burner or similar source of heat is mounted and connected to the said one end of the main feeder pipe in a manner to supply the steam under pressure which is to discharge through the apertures of the branch pipes for snow melting purposes.

The present invention further proposes the inclusion of manually adjustable means at the outer ends of the branch pipes for controlling the angular discharge of the steam from the apertures at the outer ends of the branch pipes or for completely shutting off the discharge of steam from the outer ends of the branch pipes in a manner to restrict the steam from flowing down the side of buildings and store windows or the like located on opposite sides of the street.

It is a further object of the present invention to provide snow melting devices of the type described, which is simple and capable of being assembled in an economical manner, which is effective for its intended purposes, which is capable of a long trouble free operating life and which can be manufactured and sold at a reasonable cost.

For further comprehension of the invention, and of the objects and advantages thereof, reference will be had to the following description.

2

and accompanying drawing, and to the appended claims in which the various novel features of the invention are more particularly set forth.

On the accompanying drawings forming a material part of the present disclosure:

Fig. 1 is a plan view of a street intersection provided with a snow melting device constructed in accordance with the present invention.

Fig. 2 is a longitudinal vertical sectional view taken on the line 2—2 of Fig. 1.

Fig. 3 is a partial enlarged vertical sectional view taken substantially on the line 3—3 of Fig. 1.

Fig. 4 is an enlarged partial vertical sectional view taken on the line 4—4 of Fig. 1.

Fig. 5 is an enlarged partial vertical sectional view taken on the line 5—5 of Fig. 1.

Fig. 6 is an enlarged horizontal sectional view taken at the junction of one set of branch pipes with the main feeder pipe.

Fig. 7 is an enlarged transverse sectional view of the end of one of the branch pipes taken on the line 7—7 of Fig. 1.

Fig. 8 is a plan view similar to a portion of Fig. 1, but illustrating a modification of the present invention.

Fig. 9 is an enlarged longitudinal sectional view of the end of one of the branch pipes shown in Fig. 8.

Fig. 10 is a transverse sectional view taken on the line 10—10 of Fig. 9.

Fig. 11 is a transverse sectional view taken on the line 11—11 of Fig. 9.

Fig. 12 is a view similar to Fig. 9, but showing a different position of the parts.

35 The snow melting device, according to the first form of the present invention illustrated in Figs. 1 to 7, is mounted above a street intersection having crossing street surfaces 15 and 16. The street surfaces 15 and 16 are bounded on their

40 two sides by sidewalks 17 and buildings 18 designated by the sectional portions at the four corners of Fig. 1.

The snow melting device includes a main feeder pipe 19 which is substantially of cruciform shape 45 to have one length of pipe 19^a extended parallel to the street surface 15 and a second length of pipe 19^b extended parallel to the street surface 16. From Fig. 1, it will be noted that the lengths of pipes 19^a and 19^b forming the main feeder pipe 19 are disposed above the sidewalks 17 along one of the sides of the street surfaces 15 and 16.

At the point where the lengths of pipe 19^a and 19^b forming the main feeder pipe 19 cross one another, they are joined by a four-way pipe fitment 20. Each of the lengths of pipe 19^a and

^{19b} is made up of a plurality of end aligned lengths of pipe joined together by four-way pipe fitments ²¹ and mounted on three outer ends of the lengths of pipe ^{19a} and ^{19b}, there are T-shaped fitments ²². Threaded into the fitments ²¹ and ²², to extend in opposite directions from the main feeder pipe ¹⁹ and parallel to the street surfaces ¹⁵ and ¹⁶, there are branch pipes ²³ and ²⁴. The four-way connections ^{21a}, located above two corners of the sidewalks ¹⁷, are similar in construction to the four-way connection ²⁰ as will become clear as this specification becomes clear. The remaining outer end of the length of pipe ^{19a} is provided with an elbow fitment ²⁵ for a purpose which will also become clear as this specification proceeds.

Referring now to Figs. 2 and 5, the four-way fitment ²⁰ and each of the four-way fitments ^{21a} is formed at its bottom with a depended internally-threaded socket ²⁶. Vertically extended posts ²⁷ are threaded at their top ends into the sockets ²⁶. Mounted on the bottom ends of the posts ²⁷, there are foot portions ²⁸ which are bolted to the sidewalks ¹⁷. Mounted on the lengths of pipe ^{19a} and ^{19b}, inwardly of the T-shaped fitments ²², there are collars ²⁹ that fit snugly about the lengths of pipe ^{19a} and ^{19b}. At their bottoms, the collars ²⁹ are formed with depending internally-threaded sockets ³⁰ into which the top ends of vertical posts ³¹ are threaded. At their bottom ends, the posts ³¹, as in the case of the post ²⁷, have foot portions ³² bolted to the sidewalks ¹⁷.

As best shown in Fig. 2, the posts ²⁷ and ³¹ are of equal length and combine to support the main feeder pipe ¹⁹ and the branch pipes ²³ and ²⁴ at a level above the street surfaces ¹⁵ and ¹⁶ so as not to interfere with vehicular traffic on the street surfaces and pedestrian traffic on the sidewalks ¹⁷.

The branch pipes ²³ are longer than the branch pipes ²⁴ and extend completely across the streets and stop short of the buildings ¹⁸ at the opposite side of the street. The branch pipes ²⁴ extend just to the adjacent buildings ¹⁸ at the sides of the streets on which the lengths of pipe ^{19a} and ^{19b} of the main feeder pipe are located. The outer ends of branch pipes ²³ and ²⁴ are closed by caps ³³ that are threaded into position. Along their lengths, the branch pipes ²³ and ²⁴ have apertures ³⁴. As best shown in Fig. 7, the apertures ³⁴ are arranged in sets of two apertures. The two apertures of one set are located at either end of the horizontal diametral axis and the two apertures of the other set are diverged outward and upward on opposite sides of the vertical diametral axis of the branch pipes. The apertures ³⁴ are of relatively small diameter to discharge steam under pressure in a fine spray to melt the falling snow before it can fall on the street surfaces ¹⁵ and ¹⁶ and the sidewalks. It is appreciated, of course, the spray of steam under pressure will be discharged upward and outward and laterally outward in opposite directions from either side of the branch pipe ²³ and ²⁴.

The branch pipe ^{23a} which extends from the one four-way fitment ^{21a} is formed of end aligned pipe sections joined together by three-way or T-shaped fitments ³⁵, see Fig. 1. There is one T-shaped fitment for each of the branch pipes ^{23b} extended from the length of pipe ^{19a} between the four-way fitment ²⁰ and the other four-way fitment ^{21a}, and those branch pipes ^{23b} are joined

at their ends remote from the length of pipe ^{19a} to the T-shaped fitments ³⁵.

In all other respects, the branch pipes ^{23a} and ^{23b} are similar to the branch pipes ²³, with the exception that the outer ends of the branch pipes ^{23b} are joined to the T-shaped fitments ³⁵ rather than being closed by end caps ³³.

Mounted in each of the branch pipes ²³, ^{23a}, ^{23b} and ²⁴, closely adjacent their connections with the lengths of pipe ^{19a} and ^{19b}, there is a manually operable valve ³⁶. The valves ³⁶ are normally open, but provide a means for individually shutting off the branch pipes wherever it becomes necessary to repair or replace one of the branch pipes without requiring the shutting off of the entire system.

Means is provided for supplying steam under pressure into the main feeder pipe to discharge from the apertures ³⁴ of the branch pipes. The steam supply means is housed within a hollow ³⁷, see Fig. 3, formed in the sidewalk ¹⁷ below the end of the main feeder pipe ¹⁹ which has the elbow ²⁵ mounted thereon. The top wall of the hollow ³⁷ has an entrance opening ³⁸ which opens upward through the sidewalk. The entrance opening ³⁸ is closed by a pivotally mounted trap door ³⁹ which has its top face flush with the sidewalk ¹⁷. Mounted on the one wall of the hollow ³⁷ beneath the trap door ³⁹, there are foot rungs ⁴⁰ forming a ladder so that when the trap door ³⁹ has been pivoted open one can climb down into the hollow ³⁷.

The steam supply means includes a steam generator ⁴¹ mounted in position over an oil burner ⁴² that rests on the floor of the hollow ³⁷. Water is supplied to the steam generator ⁴¹ through a pipe ⁴³ which extends from the hollow ³⁷ and is connected to a source of water under pressure. A valve ⁴⁴ mounted in the pipe ⁴³ controls the flow of water through the pipe ⁴³ into the steam generator ⁴¹.

Steam produced within the generator ⁴¹ is conveyed therefrom by a pipe ⁴⁵. The pipe ⁴⁵ exits through the top wall of the hollow ³⁷ and is connected at its top end to the elbow fitment ²⁵ mounted on the end of the length of pipe ^{19a} of the main feeder pipe ¹⁹. The steam generator ⁴¹ is provided with the usual safety valve ⁴⁶, pressure gauge ⁴⁷ and sight glass ⁴⁸ in which the water level within the steam generator ⁴¹ can be determined. Mounted in the exit pipe ⁴⁵, within the hollow ³⁷, there is a manually operable valve ⁴⁹.

The oil burner ⁴² is supplied with oil from a storage tank ⁵⁰ mounted in an elevated position on a pedestal ⁵¹. At its top, the storage tank ⁵⁰ is provided with a filler spout ⁵² closed by a removable cap ⁵³. The filler spout ⁵² is exposed within the entrance opening ³⁸ so that when the trap door ³⁹ is opened, the supply of oil within the tank ⁵⁰ can be replenished through the filler spout.

The bottom of the storage tank ⁵⁰ is connected to the oil burner by means of a pipe ⁵⁴. Mounted in the pipe ⁵⁴ there is a manually operable valve ⁵⁵ which can be shut off cutting off the supply of oil to the oil burner ⁴².

Extending from the back of the oil burner ⁴² there is a flue pipe ⁵⁶ for carrying away the gases of combustion. The top end of the flue pipe ⁵⁶ exits through the top wall of the hollow ³⁷ closely adjacent the pipe ⁴⁵, see Figs. 2 and 3. Supported above the outer end of the flue pipe ⁵⁶, there is a hood ⁵⁷ for closing the top end of the pipe. The end of the flue pipe ⁵⁶ extends a suffi-

cient distance above the sidewalk 17 so that water flowing on the sidewalk will not enter the top end of the flue pipe and flow down into the oil burner 42.

The operation of the snow melting device is as follows:

When a snow storm is expected or at the moment the snow starts falling, someone enters the hollow 37 through the open trap door 39 and starts the oil burner 42. The valve 49 is closed and the gauge 47 is watched. When the desired pressure is built up within the steam generator 41, as determined by the gauge 47, the valve 49 is reopened so that the steam under pressure can discharge from the pipe 45 and into the end of the main feeder pipe 19. The steam will flow through the lengths of pipe 19^a and 19^b forming the main feeder pipe and then into the various branch pipes. From the branch pipes the steam will be discharged in a fine spray through the apertures 34 to melt the snow as it falls through the spray of steam. The melted snow will then fall as rain and be carried away by the usual sewage system. The oil burner 42 is allowed to operate as long as the snow continues to fall. When the snow fall stops, the oil burner 42 is again shut off.

The modification of the invention shown in Figs. 8 to 12 is characterized by the provision of means for independently controlling the flow of steam under pressure from the outermost apertures 34^a of the branch pipes 23 and 24. This means is provided for keeping the steam from contacting the surfaces of the buildings 18 and especially from dirtying the windows of the buildings. The control means is characterized by a sleeve 60 rotatively mounted on the outer end of each of the branch pipes 23 and 24. The sleeves 60 are restricted to rotate through substantially one-sixth of a complete turn relative to the branch pipes 23 and 24 by means of pins 61 extended radially from the branch pipes and through elongated circumferential slots 62 formed in the sleeves 60.

Extended radially from the sleeves 60, there are bosses 63 through which clamp screws 64 are threadedly engaged. The clamp screws 64 function to secure the sleeves 60 in the desired rotative positions on the branch pipes 23 and 24. When the clamp screws 64 are loosened, they provide a convenient grip by which the sleeve 60 can be turned in one direction or the other relative to the branch pipes.

For each of the endmost apertures 34^a of the branch pipes 23 and 24, the sleeves 60 have a pair of apertures 65 and 66 and an unapertured portion all within a sixteen degree arc of the sleeves 60. The apertures 65, see Fig. 9, are extended radially through the sleeves 60 concentric with the apertures 34^a. When the apertures 65 are aligned with the apertures 34^a, the steam will be permitted to discharge in sprays projected at right angles to the lengths of the branch pipes 23 and 24 as though the sleeves 60 were not present. The apertures 65 are aligned with the apertures 34^a when the pin 61 is located at the one end of the slot 62.

When the sleeves 60 are turned to a position in which the pins 61 are located intermediate the ends of the slots 62, the apertures 66 become aligned with the apertures 34^a, as shown in Fig. 12. The apertures 66 are angled at substantially forty-five degrees from the caps 33 that close the free ends of the branch pipes 23 and 24. The inner ends of the apertures 66 are concentric with

the outer ends of the apertures 34^a to cause the steam discharging from the apertures 34^a to be directed away from the buildings 18 so as not to flow down the buildings and dirty the windows thereof.

When the sleeves 60 are turned still further in a clockwise direction as viewed in Figs. 10 and 11, the pins 61 will be located at the ends of the slots 62 remote from the ends in which they are located when the apertures 65 are aligned with the apertures 34^a. In those positions of the sleeves 60, the apertures 34^a will be completely closed so that no steam will be discharging from the apertures 34^a at the outer ends of the branch pipes 23 and 24.

In all other respects, the modification of the invention shown in Figs. 8 to 12 is similar to the first form and like reference numerals are used to identify like parts.

On the drawings, the snow melting device is shown in use in connection with urban streets; however, it is appreciated that the device can also be used in connection with rural roads. When being used on rural roads, some difficulty may be encountered from wind blown drifts and that can be dealt with by depending apertured pipes from the outer ends of the branch pipes 23 and 24 which is all within the scope and intent of the present invention.

While I have illustrated and described the preferred embodiments of my invention, it is to be understood that I do not limit myself to the precise constructions herein disclosed and the right is reserved to all changes and modifications coming within the scope of the invention as set forth in the appended claims.

Having thus described my invention, what I claim as new and desire to secure by United States Letters Patent is:

1. A device for preventing the accumulation of snow on a street, comprising a main feeder pipe supported in an elevated position above the street so as not to interfere with the movement of vehicular and pedestrian traffic on the street, branch pipes extended laterally in opposite directions from said feeder pipe and parallel to the street surface, caps closing the outer ends of said branch pipes, apertures in said branch pipes arranged in alternate sets at spaced positions along the length thereof, one set of apertures being located at either end of the horizontal diametral axis, the other set of apertures being extended upward and outward on opposite sides of the vertical diametral axis of said branch pipes, and means for generating steam connected to one end of said feeder pipe so constructed and arranged that steam fed into said main feeder pipe will discharge through said apertures to melt falling snow before it reaches the street surface,
- 45 said branch pipes having means at their ends remote from said main feeder pipe for controlling the angle of discharge of the steam or for completely preventing the discharge of steam from the apertures at the outer ends of the
- 50 branch pipes, said control means for said branch pipes comprising sleeves snugly fitted onto the outer ends of said branch pipes to be turned relative thereto, means restricting rotation of said sleeves relative to said branch pipes to substantially one-sixth of a complete turn, said sleeves having for each of the respective apertures of said branch pipes a set of spaced apertures and an unapertured portion, and means for holding said sleeves in a desired rotative position in which
- 55 either one of said apertures or the unapertured
- 60
- 65
- 70
- 75

portions are aligned with the apertures of the branch pipes.

2. A device for preventing the accumulation of snow on a street, comprising a main feeder pipe supported in an elevated position above the street so as not to interfere with the movement of vehicular and pedestrian traffic on the street, branch pipes extended laterally in opposite directions from said feeder pipe and parallel to the street surface, caps closing the outer ends of said branch pipes, apertures in said branch pipes arranged in alternate sets at spaced positions along the length thereof, one set of apertures being located at either end of the horizontal diametral axis, the other set of apertures being extended upward and outward on opposite sides of the vertical diametral axis of said branch pipes, and means for generating steam connected to one end of said feeder pipe so constructed and arranged that steam fed into said main feeder pipe will discharge through said apertures to melt falling snow before it reaches the street surface, said branch pipes having means at their ends remote from said main feeder pipe for controlling the angle of discharge of the steam or for completely preventing the discharge of steam from the apertures at the outer ends of the branch pipes, said control means for said branch pipes comprising sleeves snugly fitted onto the outer ends of said branch pipes to be turned relative thereto, means restricting rotation of said sleeves relative to said branch pipes to substantially one-sixth of a complete turn, said sleeves having for each of the respective apertures of said branch pipes a set of spaced apertures and an unapertured portion, and means for holding said sleeves in a desired rotative position in which either one of said apertures or the unapertured portions are aligned with the apertures of the branch pipes, said rotation restricting means comprising pins extended from said branch pipes and passing through elongated peripheral slots formed in said sleeves.

3. A device for preventing the accumulation of snow on a street, comprising a main feeder pipe supported in an elevated position above the street so as not to interfere with the movement of vehicular and pedestrian traffic on the street, branch pipes extended laterally in opposite directions from said feeder pipe and parallel to the street surface, caps closing the outer ends of said branch pipes, apertures in said branch pipes arranged in alternate sets at spaced positions along the length thereof, one set of apertures being located at either end of the horizontal diametral axis, the other set of apertures being extended upward and outward on opposite sides of the vertical diametral axis of said branch pipes, and means for generating steam connected to one end of said feeder pipe so constructed and arranged that steam fed into said main feeder pipe will discharge through said apertures to melt falling snow before it reaches the street surface, said branch pipes having means at their ends remote from said main feeder pipe for controlling the angle of discharge of the steam or for completely preventing the discharge of steam from the apertures at the outer ends of the branch pipes, said control means for said branch pipes comprising sleeves snugly fitted onto the outer ends of said branch pipes to be turned relative thereto, means

60 5 restricting rotation of said sleeves relative to said branch pipes to substantially one-sixth of a complete turn, said sleeves having for each of the respective apertures of said branch pipes a set of spaced apertures and an unapertured portion, and means for holding said sleeves in a desired rotative position in which either one of said apertures or the unapertured portions are aligned with the apertures of the branch pipes, one aperture of each set of spaced apertures being radially extended concentric with the apertures of said branch pipes and the other aperture being angled from the outer ends of the apertures of said branch pipes and away from the closed outer ends of said branch pipes at an angle of substantially forty-five degrees.

65 4. A device for preventing the accumulation of snow on a street, comprising a main feeder pipe supported in an elevated position above the street so as not to interfere with the movement of vehicular and pedestrian traffic on the street, branch pipes extended laterally in opposite directions from said feeder pipe and parallel to the street surface, caps closing the outer ends of said branch pipes, apertures in said branch pipes arranged in alternate sets at spaced positions along the length thereof, one set of apertures being located at either end of the horizontal diametral axis, the other set of apertures being extended upward and outward on opposite sides of the vertical diametral axis of said branch pipes, and means for generating steam connected to one end of said feeder pipe so constructed and arranged that steam fed into said main feeder pipe will discharge through said apertures to melt falling snow before it reaches the street surface, said branch pipes having means at their ends remote from said main feeder pipe for controlling the angle of discharge of the steam or for completely preventing the discharge of steam from the apertures at the outer ends of the branch pipes, said control means for said branch pipes comprising sleeves snugly fitted onto the outer ends of said branch pipes to be turned relative thereto, means restricting rotation of said sleeves relative to said branch pipes to substantially one-sixth of a complete turn, said sleeves having for each of the respective apertures of said branch pipes a set of spaced apertures and an unapertured portion, and means for holding said sleeves in a desired rotative position in which either one of said apertures or the unapertured portions are aligned with the apertures of the branch pipes, said holding means comprising clamp screws threaded through apertured bosses formed on said sleeves to be tightened against said branch pipes.
